KEY RETAINER

Samuel Segal, New York, N. Y.

Application February 14, 1945, Serial No. 577,883

5 Claims. (Cl. 224—4)

1

This invention relates to a key retainer in the form of wrist strap device and specifically is concerned with novel means for concealing an emergency key and for concealing a tiltable support for holding a watch casing in a convenient viewable position when the strap device is removed from the wrist of the wearer. The object of the invention resides in the provision of a functionally and structurally improved wrist strap device wherein simplified connector means is utilized to removably sustain adjacent turned over terminals of the key concealing loop of the strap device. Another object of the invention resides in the provision of a serviceable swingable support rotatably sustained at one end of the key concealing loop and on a transverse pin removably mounted at one end of the watch casing. Other important objects, advantages and features of the invention will appear from the following detailed description taken with the accompanying drawings wherein:

Fig. 1 is a perspective view of the key retainer according to my invention, partly broken away.

Fig. 2 is a fragmentary view of Fig. 1, shown partly in section.

Fig. 3 is a perspective view of the connector.

Fig. 4 is an exploded and perspective view of the buckle and the supporting means for the swingable key.

Fig. 5 is a perspective view illustrating the watch casing sustained in a desired tiltable position.

Fig. 6 is a fragmentary side view of Fig. 5, and Fig. 7 is a fragmentary view of the key concealing loop.

In the drawings, the key retainer is generally designated R and comprises a pair of straps or strap members 10 and 11 looped over the pins 12 and 13 removably carried by corner perforated lugs or bearings 14 extending from the watch casing 15 of the watch broadly denoted W.

More particularly the strap 10 is looped over the swingable member 16 having an eye or coiled portion 17 movably but frictionally binding its pin 12 having its ends rotatably and removably retained in adjacent spaced bearings 14.

Strap 10 is provided with an elongated slot 18 to permit the reception of the swiveled tongue 19 pivotally sustained on the fulcrum pin 20 desirably held in the aligned bores 21 of the spaced legs 22 of the hasp H provided with a notch or keeper means 23 for the reception of the free terminal of the pivoted tongue or lip 19.

The limbs 22 characterize a gap 24 closely but movably receiving the one end of the emergency

key K which includes spaced lugs 25 having aligned bores 26 for receiving the fulcrum pin 20 on which the bored enlarged end 27 of the lip is also pivoted. This enlarged end 27 fits into notch 28 and with the tongue 19, key K and hasp H all mounted on the fulcrum means 20, each may be tilted relative to the fulcrum pin which is suitably anchored in the limbs 22.

The ends 29 of the strap 10 are each provided with a suitable slot or gap 30 and when their ends are turned over upon themselves and secured by suitable stitching 31 they characterize looped ends having spaced ears 32 interrupted also by the kerfs or cuts 33 to facilitate the spreading of these ears first away from each other for the reception of the lugs 34 and 35 merged with web 36 of the H-shaped connector C.

With the strap 10 also looped over coil 17 of the swingable support 16, the turned over ends 29 constituting the spaced ears 32 thereof may be quickly mounted on the connector C. This is accomplished by first spreading apart the pair of ears or sockets 32 on one end of the strap and inserting lugs 34 therein. Thereafter the other lugs 35 of the connector are inserted into the pair of ears or sockets of the other end of the strap. The strap 10 is of suitable leather, thus the ears may be desirably separated, laterally due to the kerfs 33 which also permit the ears or sockets 32 to be moved towards and away from each other in a direction normal to the plane of the body of the strap. By such action the looped ears 32 may be readily attached or disengaged from the connector. If attached the connector 35 holds strap member 10 in close end to end relation.

To mount the buckle, characterized by the hasp H and pivoted tongue 19, on the strap 10, the looped ears 32 of one end of this strap are first removed from the connector and subsequently threaded through the hasp. Thereafter the pivoted tongue is projected into the longitudinally arranged opening 18 and the previously detached loop ears 32 are again mounted on the connector. By such arrangement the strap may be considered as endless, having been previously looped over the swiveled supporting member 16 and the hasp H. It follows that the key or body K and the swingable member 16 are concealed by the now endless strap 10 and specifically between the upper reach 37 and the lower reach defined by the complementary parts or portions 38 and 39 embodying the ends 29 having the looped ears 32.

The leather strap portion or member 11 is

looped over the removably sustained pin 13 and has its ends desirably fastened by stitching 40 to constitute terminal means adapted to be threaded into the hasp whereby the pivoted tongue 19 may be interlocked with a pair of aligned openings as 41 of the inside and outside reaches 42 and 43 after which the slideable retaining loop 44 is utilized to hold the free terminal means of strap 11 against the companion strap 10. It is apparent that the straps 10 and 11 in their secured relation about the wrist of the wearer conceal the swingable key and the supporting member 16. Moreover should access be desired to the key, strap 11 is disengaged from the buckle and the shank of the key may be conveniently projected laterally from between the reaches 31 and 38 due to the relatively elongated slot 18, permitting displacement of loops 45 along the pivoted tongue 19.

Where the key retainer is disconnected from the wrist, the watch may be supported in the tilttable relation shown in Figs. 5 and 6. Thus by swinging the lower strap 10 rearwardly, the support 16 is rotated rearwardly. By such action the rotatable support constitutes a biased brace intervening the lower and upper reaches 31 and 39, and the latter characterizes a reinforced seat for the watch casing.

Various changes may be made in details of construction and arrangement of parts without departing from the spirit of the invention or sacrificing any of the advantages thereof, for example, the spaced leather straps 10 and 11 may be considered as sustained by the watch casing or in other words the latter is a support for these straps while the spreadable ears 32 also characterize sockets removably receiving the legs or projections 34 and 35 of the connector; the shank or the body of the key also characterize reinforcing means for upper and lower reaches of strap member 10; the brace 50 of the hasp may be characterized as a crown portion; and the swingable member 16, that is that portion except for its coil 17 may be considered as tail portion on which the casing 15 is seated in a viewable but oblique position.

I claim:

1. A key retainer adapted to be removably mounted on the wrist of a wearer and adapted to be removably sustained by supporting means; said retainer comprising endless strap means having upper and lower reaches, the lower reach embodying complementary parts having looped over portions defining spaced sockets, a connector interposed between said portions and having projections removably receivable in said sockets, a hasp having a crown portion and including spaced limbs defining a gap, fulcrum means traversing said gap and sustained by said limbs, a body interposed between and removably concealed by said reaches and having means swingably sustained on said fulcrum means, a tongue pivoted on said fulcrum means and removably engageable with said crown portion, a perforated strap portion, the latter and said strap means having means to hold said supporting means, and said endless strap means having a portion looped over said limbs and having an elongated slot for receiving said tongue.

2. A key retainer adapted to be removably mounted on the wrist of a wearer and adapted to be removably sustained by supporting means; said retainer comprising endless strap means having upper and lower reaches, the lower reach embodying complementary parts having looped

over portions defining spaced sockets, a connector interposed between said portions and having projections removably receivable in said sockets, a hasp having a crown portion and including spaced limbs defining a gap, fulcrum means traversing said gap and sustained by said limbs, a relatively elongated body interposed between and normally concealed by said reaches and having means swingably sustained on said fulcrum means, a tongue pivoted on said fulcrum means and removably engageable with said crown portion, a perforated strap portion, the latter and said strap means having means to removably sustain said supporting means, and said endless strap means having a portion looped over said limbs and having an elongated slot for receiving said tongue to permit displacement of said last mentioned looped over portion relative to said hasp prior to displacement of said body from between said reaches.

3. A key retainer adapted to be removably mounted on the wrist of a wearer and adapted to be removably sustained by supporting means; said retainer comprising endless strap means having upper and lower reaches, the lower reach embodying complementary parts having looped over portions defining spaced sockets, a connector interposed between said portions and having projections removably receivable in said sockets, a hasp having a crown portion and including spaced limbs defining a gap, a pin traversing said gap and sustained by said limbs, a body normally concealed by said reaches and having means swingably and removably sustained on said pin, a tongue pivoted on said pin and having a terminal removably engageable with said crown portion, a perforated strap portion, the latter and said strap means having means to removably sustain said supporting means, and said endless strap means having a portion looped over said limbs and having an elongated slot for receiving said tongue.

4. A key retainer adapted to be removably mounted on the wrist of a wearer and adapted to be removably sustained by supporting means; said retainer comprising endless strap means having upper and lower reaches, the lower reach embodying complementary parts having looped over portions defining spaced sockets, a substantially H shaped connector interposed between said portions and having projections removably receivable in said sockets, a hasp having a crown portion and including spaced limbs defining a gap, fulcrum means traversing said gap and sustained by said limbs, a body interposed between and normally concealed by said reaches and having means swingably sustained on said fulcrum means, a tongue pivoted on said fulcrum means and removably engageable with said crown portion, a perforated strap portion, the latter and said strap means having means to removably sustain said supporting means, and said endless strap means having a portion looped over said limbs and having an elongated slot for receiving said tongue.

5. A key retainer adapted to be removably mounted on the wrist of a wearer and adapted to be removably sustained by supporting means; said retainer comprising endless flexible strap means having upper and lower reaches, the lower reach embodying complementary parts having looped over portions defining swingable spaced sockets, said looped over portions having kerfs to facilitate spreading of said sockets, a connector interposed between said portions and having pro-

jections removably receivable in said sockets, a hasp having a crown portion and including spaced limbs defining a gap, fulcrum means traversing said gap and sustained by said limbs, a body interposed between and normally concealed by said reaches and having means swingably sustained on said fulcrum means, a tongue pivoted on said fulcrum means and removably engageable with said crown portion, a perforated strap portion for interlocking with said tongue, said strap portion and said strap means having means to removably sustain said supporting means, and said endless strap means having a portion looped over said limbs and having an elongated slot for receiving said tongue.
